UNITED STATES PATENT OFFICE.

JOHN BEVERLY BARNETT, OF FORT WORTH, TEXAS, ASSIGNOR, BY MESNE ASSIGNMENTS,
OF ONE-HALF TO W. M. TURNER, OF TARRANT COUNTY, TEXAS.

ADVERTISING-CLOCK.

No. 914,229.

Specification of Letters Patent.

Patented March 2, 1902.

Application filed March 11, 1902. Serial No. 420,360.

To all whom it may concern:

Be it known that I, JOHN B. BARNETT, a citizen of the United States, residing at Fort Worth, in the county of Tarrant and State 5 of Texas, have invented certain new and useful Improvements in Advertising-Clocks, of which the following is a specification.

My invention relates to advertising devices and more particularly to mechanism which 10 is actuated at regular intervals by a time mechanism; and the object is to provide novel and useful devices for displaying advertising sheets at regular intervals and to give signals at the moment when a change 15 of display is to be made.

Other objects and advantages will be 20 fully explained in the following description and the invention will be more particularly pointed out in the claims.

Reference is had to the accompanying drawings which form a part of this application and specification.

Figure 1 is a front elevation of advertising device, illustrating my invention. Fig. 2 is 25 a rear elevation of the operating mechanism. Figs. 3 and 4 are broken detail views, illustrating the manner of suspending the advertising sheets. Figs. 5 and 6 are detail views 30 of the manner of carrying the sheet suspending devices. Fig. 7 is a vertical section of the casing for the invention, showing a diagrammatic view of the operating mechanism. Fig. 8 is a detail view of the mechanism for actuating the main drive wheel. 35 Fig. 9 is a broken edge view of the wheel which is to be driven.

Similar characters of reference are used to indicate the same parts throughout the several views.

A cabinet is used to carry out the objects 40 of this invention, such as is shown in Fig. 1. A clock 1 of ordinary construction is mounted in the upper part of the cabinet. The clock is used to make and break an electric circuit 45 hereinafter described. The clock is provided with a seconds hand 2 which is mounted on an arbor 3. One or more arms 4 may be mounted on and carried by the arbor 3. If there are two arms 4, diagonally 50 opposite each other the arms 4 will strike a contact in the path of these arms every thirty seconds. A brush contact 5 is

mounted in the path of the arms 4. The brush contact 5 is insulated from the works of the clock and electrically connected with 55 the cell 25 by a wire 28 which forms a part of the electric circuit hereinafter described. The arms 4 strike the contact 5 in their annular beat and an electric circuit is made and broken every time the arms 4 touch the 60 contact 5.

The advertising sheets 6 are carried on rods 7 and the rods 7 are carried by two sprocket chains 8 and 9. The chains 8 and 9 are driven by sprocket wheels 10 and 11. 65 Idle sprocket wheels 12 of sufficient weight are mounted in the bight of the sprocket chains 8 and 9 and serve to hold said chains and the rods 7 in operative relation. The sprocket wheels 12 are mounted on a shaft 13 70 which holds these wheels in their places as the sprocket chains move. The sprocket wheel 10 is driven by a pivoted driving dog 14 which is carried by a lever 15. The dog 14 engages pins 16 which are rigid with the 75 wheel 10. A pivoted stop dog 17 engages the pins 16 to prevent backward turning of the sprocket wheels. The dog 17 is pivotally mounted on a bracket 18 which may be attached to the casing of the cabinet. The shaft 19 is journaled in brackets 20 which are attached to the interior of the cabinet. The dog 14 is actuated by a lever and magnets. Magnets 21 and 22 are mounted in the eas- 80 ing or within the cabinet. The magnets are 85 electrically connected by a bar 23. The magnet 21 is electrically connected by a wire 24 with the works of the clock 1. Cells 25 and 26 and 27 are placed in the lower part of the cabinet. The contact 5 is electrically 90 connected to the cell 25 by a wire 28. The magnet 22 is electrically connected to the cell 27 by a wire 29. The cell 26 is electric- 95 ally connected to the cell 25 and to the cell 27. The circuit is completed every time an arm 4 touches the contact 5, the arms 4 being electrically connected with the wire 24 through the works of the clock. An ar- 100 mature 30 is attached to the upper arm of the lever 15. The lever 15 is fulcrumed on a bracket 31 which may be attached to the interior of the cabinet. Every time the circuit is completed as heretofore described the armature 30 is drawn to the magnets 21 and

22. This action serves to draw the dog 14 back off of a pin 16, retracting the dog one pin. As soon as the circuit is broken, the spring 32 draws the lever 15 back to its normal position. This action causes the dog 14 to move the sprocket wheels by driving the pin 16 in front of the dog. These operations serve to revolve the wheels 10 and 11 as long as the clock is running.

10. The sheets 6 fall over the rods toward the front as the sprocket wheels turn. A sheet may be made to fall as often as desired. The number of sheets may be increased by increasing the number of the rods 7. The 15 number of sheets to fall in a minute may be increased by increasing the number of arms 4 on the seconds arbor 3, thus completing the circuit oftener. The cabinet is provided with a door 35 for access to the lower part of 20 the cabinet. The cabinet is also provided with a glass or transparent door 36 so that the advertising sheets may be seen from positions in front of the cabinet. Advertising matter is to be printed on the sheets so it can 25 be read when the sheets fall over in front. The advertising matter is generally printed on that face of a sheet which is toward the door when the sheet is in a hanging position so that the advertising matter can be seen only 30 after the sheet is released from the arms 34 and falls down in the hanging position. The sheets 6 are held in place on the rods 7 by rubber collars 33, to prevent lateral displacement of the sheets. The collars 33 are made 35 of rubber so that they can be easily adjusted and being elastic, the collars will yield enough to receive the rods and will not slide on the rods unless forced and being soft, they will not mutilate the advertising sheets. In 40 order to prevent the sheets 6 from falling over in front irregularly, each sheet is held by two arms 34, as shown in Fig. 7, until the edge of the sheet passes from under the arms 34. The sheets are thus made to fall at regular 45 intervals. It is apparent that within the scope of the appended claims variations in the assembling of the various parts of the clock and the mechanism actuated thereby may be varied without departing from this 50 invention. The rods 7 are loosely and removably mounted in sockets carried by the sprocket chains 8 and 9 so that the advertising sheets may be changed as often as desirable. The rods 7 are loosely mounted in the 55 sockets on the chains so that the rods can be removed for the purpose of placing the advertising sheets on the rods.

Having fully described my invention, what I claim as new and desire to secure by Letters 60 Patent, is,—

1. An advertising device comprising a shaft, sprocket wheels mounted on said shaft, sprocket chains mounted on said wheels and carrying sockets, bars carried in

said sockets, idle sprocket wheels and a 65 shaft holding said idle sprocket wheels at a fixed distance apart and said idle sprocket wheels being mounted in and supported by the bights of said sprocket chains and holding said sprocket chains in operative relation whereby said bars are held in place as the same are revolved, time magnetically operated mechanism for driving said sprocket wheels, and sheets hung on said bars.

2. An advertising device comprising driven 75 sprocket wheels, sprocket chains suspended on said sprocket wheels and carrying sockets, bars removably mounted in said sockets, idle sprocket wheels mounted in and supported by the bights of said sprocket 80 chains and a bar or shaft holding said idle sprocket wheels at a fixed distance and said idle sprocket wheels co-operating with said driven sprocket wheels to hold said chains at a fixed distance apart, and sheets suspended 85 on said bars.

3. An advertising device comprising carrying sprocket wheels, traveling sprocket chains mounted on said sprocket wheels and provided with sockets, bars carried in said 90 sockets, idle sprocket wheels bearingless shafts therefor holding said sprocket chains in operative relation whereby said bars are held in place during the movement of said sprocket chains, sheets suspended on said 95 bars, magnet operated gearing for driving said carrying sprocket wheels, and means for causing intermittent operation of said gearing.

4. An advertising device comprising carrying sprocket wheels, traveling sprocket chains mounted on said sprocket wheels and carrying sockets, bars carried in said sockets, idle sprocket wheels mounted in and supported by the bights of said chains and 105 serving to hold said chains and bars in operative relation, sheets suspended on said bars, gearing for driving said sprocket wheels, magnets for actuating said gearing, means for energizing said magnets, and a time 110 mechanism for causing said magnets to be energized at regular intervals.

5. An advertising device comprising a casing, a time mechanism mounted in said casing, magnets and batteries operatively connected with said time mechanism, traveling sprocket chains operating in said casing and carrying horizontally disposed bars, sheets suspended on said bars, driving sprocket 115 wheels for said chains, idle sprocket wheels 120 mounted in and supported by the bights of said chains and holding said chains and bars in operative relation, and actuating devices operatively connected to said magnets and to said driving sprocket wheels whereby said 125 sprocket chains are driven by said magnets.

6. An advertising device comprising a casing, traveling sprocket chains operating

in said casing and carrying horizontally disposed bars, sheets suspended on said bars, rubber collars mounted on said bars, one on each side of each sheet for preventing the displacement of said sheets, and means for causing said chains to travel intermittently.

5 In testimony whereof, I set my hand in

the presence of two witnesses, this 25th day of February, 1908.

JOHN BEVERLY BARNETT.
